UNITED STATES PATENT OFFICE.

FRANK HOERNER, OF LOS ANGELES, CALIFORNIA.

COMBINATION SURFACE PLATE AND PISTON ALIGNER.

Application filed November 30, 1923. Serial No. 677,921.

To all whom it may concern:

Be it known that I, FRANK HOERNER, a citizen of the United States, residing at Los Angeles, in the county of Los Angeles 5 and State of California, have invented new and useful Improvements in Combination Surface Plate and Piston Aligners, of which the following is a specification.

Although my present invention is referred to as a combination surface plate and piston aligner, it should be understood that a preferred form of my invention comprises a plate which may be used either in combination with piston aligning means or independently thereof.

It is an object of this invention to provide a surface plate, capable of use in conjunction with an arbor for use in the alignment of pistons, with novel supporting means, my preferred supporting means being in the form of a retaining block extending from the back of the said surface plate and longitudinally thereof in such manner as to permit of the support of my surface plate, or 25 my surface plate and aligning means rigidly connected therewith, by means such as an ordinary vice.

It is an object of this invention to provide a piston aligner, which may comprise an arbor or arbors or an arbor and bushings or shims rigidly supported at right angles to a surface plate, with means permitting the support of the same in an exactly vertical position, when desired, regardless of any 35 inclination or other irregularity in a bench or other work support in connection with which the same is to be used, my preferred securing means comprising a block extending substantially at right angles to the plane of a surface plate and adapted to be received between the jaws of any ordinary vice, which may be positioned and intended for the routine work of a machine shop.

It being customary to provide piston aligners with comparatively heavy bases intended to support the same from below and in an upright position, it is an object of this invention to provide means for supporting a surface plate or a piston aligner from 46 one side, and a preferred form of my invention comprises what I may term a "knock-down" piston aligner comprising an arbor or arbors adapted to be rigidly secured at right angles to a surface plate or 50 to be disconnected therefrom to permit in-

dependent use of the surface plate or to permit storage of the complete article referred to in a comparatively small space; and a preferred embodiment of my invention may comprise a surface plate provided 60 with an aperture or apertures near one end or the top thereof by which the same may alternatively be connected with an overhead supporting means, when desired.

Other objects of my invention will appear 65 from the following description of a preferred embodiment thereof, and from the appended claims, taken in connection with the accompanying drawings, in which:

Figure 1 is a perspective view showing 70 a surface plate supported from a vice and associated with additional elements constituting a piston aligner, a piston and a connecting rod being shown in place.

Figure 2 is a perspective view from another angle, showing only the essential parts of my invention, without a vice or a piston or connecting rod.

Referring to the details of that specific embodiment of my invention which I have 80 chosen for purposes of illustration, 1 may be a surface plate, provided near its lower end with an arbor 2 extending at right angles to said plate, this arbor being preferably separable from said plate and provided at its inner end 3 with retaining means such as the nut 4, adapted to engage a thread thereon and to contact with an expanded washer 5, contacting with the rear surface 6 of the surface plate 1.

This means of securing the arbor to the surface plate permits replacement of arbors having different diameters for the purpose of accommodating bearings of different sizes.

It will be understood to be of importance that the plate 1, or at least such parts thereof as may be employed in the testing of piston alignments, shall be a perfectly true and flat surface; and, when this flat surface 100 is to be used in connection with an arbor 2, for use in the manner suggested above, it will be understood to be of importance that this arbor, which may advantageously be provided with an exactly flat and true shoulder at 7, to contact with the flat face of the surface plate 1, shall be, when adjusted, exactly perpendicular to said face.

When the parts referred to are disassembled, the plate 1 may serve any of the 110

usual purposes of a surface plate; but, when an alignment is to be tested by means of my combination surface plate and piston aligner, a connecting rod 8, carrying a piston 10, may be clamped in position upon the arbor 2, or its equivalent, as by an adjustment of the nuts 8, by which the split bearing 9 may be tightened, any imperfection of alignment being then immediately apparent as resulting in a lack of parallelism between the body of the piston 10 and the adjacent flat surface of the plate 1, or apparent upon the oscillation of said piston upon its transverse axis, which should, of course, extend in a direction exactly parallel to the arbor 2.

For reasons suggested, it is advantageous to provide a surface plate 1 separable from the arbor 2; but the outstanding feature of novelty in my present invention may nevertheless be regarded as the provision of novel and highly advantageous supporting means for the parts above described, my preferred supporting means comprising a retaining block 11, shown as secured to the back of the plate 1 and as extending parallel therewith in a plane substantially at right angles thereto, this block preferably occupying an intermediate position between the respective ends of the plate 1 and being shown as adapted to be received between the jaws of a vice 12, in such manner that the verticality of the plate 1 may be established independently of the horizontality of any bench, or the like, to which the vice 12 may be secured, and independently of the verticality of the jaws 13 of said vice.

In order rigidly to support the plate 1 from a vice, it is advantageous that the block 11 shall be positioned centrally near the lower end thereof, and it may advantageously constitute practically an extension or expansion of a longitudinal reinforcing rib 14 extending toward or to the top of said plate.

Without interfering with the use of my surface plate independently of the remaining parts referred to, or as an element of my combination piston aligner, I may optionally provide the same with means permitting its rigid connection with an overhead support, my preferred means for this purpose being simply the provision of a plurality of suitable apertures 15, near the top of said plate, from which the same may be rigidly suspended, as desired, and by means of bolts or other known securing devices.

Although I prefer to form the plate 1 as

a semi-steel casting, about 18 inches long by 5 inches wide, and to provide the same with a 1 1/4 inch arbor suitable for use in testing the alignment of various pistons of known types, it will be understood that the actual dimensions of the parts of my present invention are not material to the novelty or utility thereof, and that I may optionally provide a plurality of arbors of different sizes for alternative use, or I may optionally provide or permit the use of various bushings 16, or shims, or the like, in connection with a single arbor, which may either be formed integral with a plate 1 or perfected independently thereof for rigid attachment in the manner above described or in any other preferred way.

Although I have herein described but one complete embodiment of my invention, it will be understood that various features thereof might be independently employed, and also that various modifications might be made therein without departure from the spirit and scope of my invention, as the same is indicated above and in the following claims.

What I claim is:

1. A piston aligner comprising a face plate which is greater in width than the piston to be aligned, there being an aperture formed centrally of the face plate adjacent one end thereof, an arbor having a reduced end extending through said aperture with the enlarged end projecting from the face of the face plate and providing a shoulder bearing against the faced surface of the face plate, and a nut threaded onto the reduced end of the arbor on the back side of the face plate for tightening the arbor to the face plate.

2. A piston aligner comprising a face plate which is greater in width than the piston to be aligned, there being an aperture formed centrally of the face plate adjacent one end thereof, an arbor having a reduced end extending through said aperture with the enlarged end projecting from the face of the face plate and providing a shoulder bearing against the face of the face plate, a nut threaded onto the reduced end of the arbor on the back side of the face plate for tightening the arbor to the face plate, and a block secured against the back side of the face plate permitting the device to be readily mounted upon a vice.

In testimony whereof I have signed my name to this specification.

FRANK HOERNER.
